UNITED STATES PATENT OFFICE.

ERNEST THOMPSON WILLOWS, OF CARDIFF, ENGLAND.

AIRSHIP, AEROPLANE, OR AEROSTAT.

1,061,434.

Specification of Letters Patent.

Patented May 13, 1913.

Application filed June 16, 1910. Serial No. 567,254.

To all whom it may concern:

Be it known that I, ERNEST THOMPSON WILLOWS, a subject of the King of Great Britain and Ireland, residing at 2 Dumfries Place, Cardiff, England, have invented certain new and useful Improvements Relating to Airships, Aeroplanes, or Aerostats, of which the following is a specification.

This invention relates to air ships and has for its object to provide means, simple in construction and convenient and effective in operation for maneuvering air ships or the like.

It has before been proposed so to mount the axis of rotation of an aerial propeller that it may be capable of angular movement or partial rotation in its own plane in order to effect propulsion in any desired direction, but hitherto this has not been done in such manner as to permit of convenient and ready operation and this is a particular object of the present invention.

According to the invention I mount the spindles to which the propellers are secured in such manner as to be capable of a movement of partial rotation in the plane of their axes and I carry each of the propeller spindles upon a tubular member or frame part through which a live axle passes by which the drive is communicated to the propeller spindles, a set of bevel or other gear wheels being advantageously provided to communicate movement from the end of the live axles to the respective propeller spindles, while similarly the tubular member or frame part is so provided or cut away as to permit of the drive being communicated from the engine to the live axle referred to in such manner that the partial movement of rotation is allowed to the tubular part without interference with the driving gear.

The invention is illustrated in the accompanying drawings in which—

Figure 1 is a diagrammatic part-plan view of the invention applied to the frame of an air ship. Fig. 2 is a longitudinal elevation corresponding to Fig. 1. Fig. 3 is a detail plan view on an enlarged scale of the coupling of the transverse tubular members. Fig. 4 is an elevation of a modified arrange-

ment of the transverse tubular member and the engine, and showing also a chain or belt drive.

In carrying the invention into effect in one convenient manner, as shown in Figs. 1, 2 and 3, in its application to the frame *a* of an airship which is connected to an aerostat by any suitable means I provide at each end of the frame *a* a set of propellers *b*, a propeller being respectively mounted upon the extremity of each propeller spindle *c*. Each propeller spindle *c* is carried at the extremity of the tubular member or frame *d* which is suitably mounted in the frame *a* of the machine. The member or frame may be composed of one continuous or two tubular members or frames at the respective extremities of which the respective spindles *c* are carried advantageously in a central position, and are rotated from a corresponding live axle *e*, carried within the tubular member *d*, by means of bevel wheels *c*¹ *e*¹. It is preferable that one of the bevel wheels *c*¹ should be disposed upon the corresponding spindle in advance of the center-line or axis of the axle *e* while the other bevel wheel *c*¹ is disposed to the rear of the said center line. By this arrangement the tendency of the tubular member *d* to turn or rotate under the influence of the power transmitted through the bevel gear is overcome as the two extremities of the tubular member tend to rotate in opposite directions. I may, however, mount the spindle *c* in a plane above the central plane of the tube so as to balance the tendency to turn under the thrust of the bevel gear *c*¹ *e*¹ by the forward thrust on the propeller shaft *c* tending to turn the tube *d* in the opposite direction to the thrust on the bevel gear. The tubular member, or frame *d* referred to is interrupted at that part *d*¹ where the drive is communicated to the live axle *e* contained in it, a connection being made by means of one or more coupling members *d*² which are so disposed as to permit to them a sweep or angular movement of about 180°, more or less, that is to say, such a movement that the coupling or connecting member *d*² will clear the driving shaft *f*, driving chain or other suitable gear em- 100

ployed to impart movement to the live axle or axles *e*. The latter are at their oppositely disposed extremities provided with a bevel gear *e*¹ which gears with a correspond-
5 ing wheel *c*¹ mounted upon the propeller shaft *c* so that thus the drive is simultaneously communicated to propeller shafts at each side.

I advantageously provide the air ship or 10 aeroplane frame *a* with a central part upon which the engine *g* and the seat of the driver is mounted, and I provide an outwardly extending bracket or frame *a*¹ on each side for the purpose of carrying the tubular member *d* carrying at its extremities the propeller shafts *c* referred to. For the purpose of adjusting the propellers in any suitable position the joint or connecting member above referred to is connected to an operating 15 member in a position convenient of access to the driver, so that thus he may be able to rotate the tubular member in one direction or the other to the extent required according to the position he requires the 20 propellers to assume in maneuvering. Suitable gear for this purpose may consist of a hand wheel *h* provided with a nut *h*¹ for communicating movement to the tubular member or frame part *d* referred to. The 25 rotation of the nut *h*¹ by the wheel *h* causes a longitudinal movement of the rod *i* which is provided with a screw-thread to engage with the nut *h*¹. The rod *i* is connected by a link *j* to a lug *k* formed on the tubular 30 members *d*² or upon one of the tubular members *d*. The longitudinal movement of the rod *i* causes the angular movement of the couplings *d*² and tubular members *d* and consequently the rotation of the propellers *b* about the axle *e*.

In the modification shown in Fig. 4 the drive is transmitted by means of belts or chains from the engine which is disposed at the middle of the tubular member *d*, and the 45 construction is such as to obviate the use of all bevel gearing. The tubular member *d* is in two parts which are connected together by a bracket or framing *d*³ adapted to receive the engine *g*¹ which is secured in position with its shaft transversely disposed to the member *d*. The drive is taken direct from the engine to the spindles *c*¹ by belts which may be crossed or open or chains *f*¹ which pass around pulleys or chain wheels 50 *c*² mounted upon the spindles *c*¹. A handle *h*² or other suitable means such as a worm and wheel, is provided by which the tubular member *d* together with the engine may be partially rotated for the adjustment 55 of the position of the propeller axes as may be desired, such rotation of the member *d* being limited only by the requirements of the working of the engine. It will however be understood that I may use two propellers

on each extremity of the tubular member *d* mounted on the front side or after side instead of only one as illustrated.

What I claim as my invention and desire to secure by Letters Patent is:

1. In apparatus for propelling and maneuvering airships and the like the combination comprising tubular members, means connecting together said tubular members, driving spindles within said tubular members, means for simultaneously rotating said spindles in opposite directions, casings mounted at the free ends of said tubular members, propeller shafts within said casings, said propeller shaft being driven by the spindles, propellers on said propeller shafts, and means for simultaneously varying the position of the propellers.

2. In apparatus for propelling and maneuvering airships and the like the combination comprising two tubular members, a spherical member fixedly connecting together the tubular members, driving spindles within said tubular members, gears connecting said spindles inclosed within said spherical member, means for operating said gears, casings mounted at the ends of said tubular members, propeller shafts within said casings, said propeller shafts being driven by the spindles, propellers on said shafts, and means for rotating the tubular members for the purpose of adjusting the position of the propellers.

3. In apparatus for propelling and maneuvering airships and the like the combination comprising tubular members, a spherical member connecting together the two tubular members, driving spindles within said tubular members, gears connecting said spindles, said gears being inclosed within said spherical member, means for driving the gears, casings mounted at the ends of said tubular members, propeller shafts within said casings, bevel wheels between the propeller shafts and the spindles, the bevel wheels on opposite sides of the airship being so disposed that the reactive forces set up by the bevel wheels when under power are balanced, propellers mounted on said propeller shafts, and means connected to the spherical member for varying the inclination of the propellers.

4. In apparatus for propelling and maneuvering airships and the like the combination comprising two tubular members, a spherical member connecting together the tubular members, driving spindles within said tubular members, gears connecting said spindles, said gears being inclosed within said spherical member, means for driving said gears, casings mounted at the ends of said tubular members, propeller shafts within said casings, bevel wheels between the propeller shafts and the spindles, said bevel

wheels being disposed in diametrically opposite positions in relation to the axis of the spindles for the purpose of balancing the reactive forces set up by the bevel wheels
6 when under power, propellers mounted on said propeller shafts, and means connected to the spherical member for simultaneously varying the inclination of the propellers.

In testimony whereof I have hereunto signed my name to this specification in the 10 presence of two subscribing witnesses.

ERNEST THOMPSON WILLOWS.
